ROTATING DIE HEAD WITH CAM OPERATED RADIAL CHASERS

Harry V. Packer, Cleveland, Ohio, assignor to
The Oster Manufacturing Company, Cleveland,
Ohio, a corporation of Ohio

Application August 20, 1948, Serial No. 45,252

9 Claims. (Cl. 10—122)

1

This invention relates to thread cutter die heads and has for its object to provide means by which the dies may be simultaneously moved radially out of work engaging position during operation.

The invention also has for an object to provide a die head by means of which the dies may be readily adjusted radially to operate on work-pieces of different diameters and to also provide means by which the die may be instantly shifted from any adjusted operating position to an inoperative position during rotation of the head.

With the above and other objects in view the invention may be said to comprise the die head as illustrated in the accompanying drawings and hereinafter described, together with such variations and modifications thereof as will be apparent to one skilled in the art to which the invention pertains.

Reference should be had to the accompanying drawings forming a part of this specification in which:

Figure 1 is a front elevation of a die head embodying the invention showing the dies mounted in operative position.

Fig. 2 is a top plan view of the die with a portion broken away and shown in horizontal section;

Fig. 3 is a central longitudinal section through the die head taken on the line indicated at 3—3 in Fig. 1;

Fig. 4 is a fragmentary section taken on the line indicated at 4—4 in Fig. 3; and

Fig. 5 is a fragmentary front elevation of the die head showing the dies shifted to an inoperative position.

The die head of the present invention is adapted for attachment to the end of a suitable driving spindle and in the accompanying drawings the die head is shown attached to the end of a tubular drive spindle 1. The spindle 1 is driven by suitable means which may include a gear 2 attached to the spindle adjacent its end and positioned within a suitable housing 3. The spindle 1 projects through an opening in the housing 3 to receive a suitable adapter 4 that is secured thereto by means of bolts 5. The adapter 4 has a circumferential flange 6 to which the die head is attached, the die head having a body 7 provided with a peripheral flange 8 at its inner end that is secured to the flange 6 of the adapter 4 by means of bolts 9.

The body 7 is exteriorly cylindrical outwardly of the flange 8 and has a handwheel 10 rotatably mounted thereon adjacent the flange 8, the handwheel 10 being positioned by means of a retaining ring 11 secured to the body 7 outwardly there-

2

of. The ring 11 is provided with circumferentially extending slots 12 which receive attaching bolts 13 that extend through the slots and are screwed into the body 7. By means of the bolt-slot connection the ring 11 can be secured in various adjusted positions circumferentially with respect to the body of the die head. The ring 11 is provided with an aperture 14 that forms a locking recess and a projecting stop lug 15 spaced angularly from the aperture 14.

At its outer end the body 7 is provided with radially disposed die receiving sockets 16 in which thread cutting dies 17 are slidably mounted. The dies 17 are retained in the sockets and secured in various adjusted positions therein by means of an annular cam 18 that is rotatably mounted upon an outer end portion 19 of the body 7 that is of reduced diameter. The cam 18 is retained on the reduced end portion 19 of the body by means of a threaded ring 20 screwed into the outer end of the body 7 and having a peripheral retaining flange 21 overlying the inner portion of the cam 18, the cam 18 being provided with a cylindrical internal shoulder 22 that bears upon the periphery of the flange 21. The cam 18 has a plurality of circumferentially extending ribs 23 that are circumferentially spaced upon the inner face thereof. The cam ribs 23 correspond in number to the number of dies in the head and the angular spacing of the cam ribs corresponds to the angular spacing of the dies, each rib 23 engaging a transverse slot 24 in a die 17 and each of the ribs 23 being inclined in the same direction with respect to its circumferential path of travel to simultaneously move the dies radially toward or away from the axis of the head upon a turning movement of the cam 18 with respect to the body 7 of the head.

A connection is provided between the handwheel 10 and the cam 18 for imparting turning movements to the cam 18 to simultaneously disengage the dies from the work during operation of the machine. The cam 18 is provided with a radially outwardly projecting portion 25 that is connected to the handwheel 10 through a member 26 which serves as a connecting link between the cam and handwheel. The member 26 is connected to the extension 25 of the cam by means of a pivot 27 disposed parallel to the axis of the head and is part of a lost motion connection between the cam 18 and the handwheel 10 which permits the handwheel 10 to have a limited angular movement with respect to the cam 18. The connection between the link 26 and the handwheel 10 is such that the link 26 swings about its pivot during a relative turning movement of the handwheel and cam and this pivotal

movement of the link is utilized to release a locking connection between the cam 18 and the body 7 of the head.

As herein shown the lost motion between the handwheel and cam is provided by means of a laterally projecting pin 28 carried by the link 26 and projecting into an elongated slot 29 in the handwheel 10. The slot 29 is provided with a face 30 at one side edge thereof that is inclined with respect to its path of circumferential travel and that acts upon the pin 28 to impart an angular movement to the link 26. The link 26 is pivoted intermediate its ends and the portion thereof on the side of the pivot 27 opposite that carrying the pin 28 has a locking projection 31 projecting radially inwardly therefrom that is adapted to engage in the aperture 14 in the ring 11. When the dies 17 are in operative position the locking projection 31 engages in the aperture 14 of the ring 11 to hold the cam 18 against turning movements with respect to the body 7 of the head.

The member 26 is yieldably held in its locking position and is moved to the releasing position shown in Fig. 5 when the handwheel 10 is turned upon the body 7 in a direction to engage the inclined cam face 30 with the pin 28. The handwheel 10 has a radially disposed boss 32 on its outer face that is provided with a radial bore 33 in which is mounted a radially movable plunger 34 that has a rounded inner end bearing upon the outer edge of the member 26. The plunger 34 has a stem 35 of reduced diameter which extends outwardly and that is guided in a threaded plug 36 in the outer end of the bore 33. The plunger 34 is pressed inwardly against the member 26 by a coil spring 37 surrounding the stem 35 and interposed between the plunger 34 and the plug 36.

As shown in the drawings, the dies 17 have their cutting faces 38 facing counter-clockwise and the handwheel cam 30 is so disposed with respect to the connecting member 26 that the member 26 is swung in a direction to release the locking projection 31 and to actuate the cam 18 in a direction to release the dies 17 from the work upon movement of the handwheel 10 on the body 7 of the head in a clockwise direction. During the thread cutting operation the head is rotated counter-clockwise with the cam locked as shown in Fig. 1. If during the threading operation it is desirable to discontinue the cutting operation the operator simply grasps the handwheel 10, retarding its rotation and causing it to turn in a clockwise direction with respect to the body 7 of the head. This turning movement to the handwheel engages the cam face 30 with the pin 28 and swings the connecting member 26 in a direction to move the locking projection 31 outwardly against the action of the spring 37. When the pin 28 reaches the inner end of the slot 29 the member 26 will be moved to a position where the locking projection 31 is released from the ring 11 as shown in Fig. 5 and the cam 18 will be connected through the member 26 to the handwheel for turning movement therewith. Further clockwise turning movement of the handwheel 10 will impart a corresponding turning movement to the cam 18 which will simultaneously shift the dies 17 out of work engaging position. The extent of turning movement of the cam is limited by the stop lug 15 on the ring 11 which is in the path of the connecting member 26, permitting an angular movement of the cam 18 sufficient to disengage the dies from the work. The dies 17 may

be reset to work engaging position by a counter-clockwise turning movement of the handwheel 10.

The radial adjustment of the dies 17 for operation on workpieces of different diameters is effected by circumferential adjustments of the ring 11 by means of the bolts 13 and slots 12. The position to which the locking recess 14 on the body 7 is adjusted determines the positions of the cam ribs 23 with respect to the dies when the cam ring is locked by engagement of the projection 31 in the aperture 14. In all positions of angular adjustment of the ring 11 the handwheel 10 and cam 18 are permitted the same relative turning movement, since the stop lug 15 is adjusted with the locking recess 14 and is always at the same angular distance from the locking recess 14.

It is to be understood that in accordance with the provisions of the patent statutes, variations and modifications of the specific devices herein shown and described may be made without departing from the spirit of the invention.

What I claim is:

1. A die head comprising a body portion adapted for attachment to a rotary spindle and having circumferentially spaced sockets that converge toward its axis for slidably receiving thread cutting dies, a die adjusting cam rotatably mounted in said head and having circumferentially extending die engaging portions inclined in the same direction with respect to their circumferential path of travel to move the dies simultaneously toward or away from the head axis, a handwheel extending around the periphery of the head and mounted to turn thereon, a lost motion connection between said handwheel and cam permitting a small relative angular movement of the handwheel with respect to said cam, and means for releasably locking said cam to said body portion to positively hold said cam against turning movements with respect to said body portion of the head comprising a movable member operably connected to said cam and handwheel to be moved into and out of its cam locking position by relative angular movements of said handwheel and cam.

2. A die head comprising a body portion adapted for attachment to a rotary spindle and having circumferentially spaced sockets that converge toward its axis for slidably receiving thread cutting dies, a die adjusting cam rotatably mounted in said head and having circumferentially extending die engaging portions inclined in the same direction with respect to their circumferential path of travel to move the dies simultaneously toward or away from the head axis, a handwheel extending around the periphery of the head and mounted to turn thereon, a lost motion connection between said handwheel and cam including an angularly movable connecting link, and locking means actuated by said link for holding said cam against turning movements with respect to said body portion of the head.

3. A die head comprising a body portion adapted for attachment to a rotary spindle and having circumferentially spaced sockets that converge toward its axis for slidably receiving thread cutting dies, a die adjusting cam rotatably mounted in said head and having circumferentially extending die engaging portions inclined in the same direction with respect to their circumferential path of travel to move the dies simultaneously toward or away from the head axis, a handwheel extending around the periphery of the head and mounted to turn thereon, a lost motion con-

nection between said handwheel and cam including an angularly movable connecting link, and a latch member carried by said cam and operably connected to said link for movement into and out of locking engagement with said body portion of the head.

4. A die head comprising a body having an inner end portion adapted for attachment to the end of a driving spindle and an outer end portion provided with angularly spaced sockets to receive thread cutting dies, a handwheel rotatably mounted on said body, a cam rotatably mounted on the body outwardly of said handwheel and having circumferentially spaced portions inclined in the same direction with respect to their path of circumferential travel for engagement with the thread cutting dies in said sockets to simultaneously move the same radially, a link having a pivotal connection to said cam and a pin and slot connection to said handwheel in which the slot is at an inclination to its circumferential path of travel whereby an angular movement is imparted to the link upon a turning movement of the handwheel with respect to said cam, and a locking member actuated by said link and movable into and out of a position in which it holds the cam against turning movements with respect to said body.

5. A die head comprising a body having an inner end portion adapted for attachment to a driving spindle and an outer end portion having angularly spaced sockets converging toward the axis of the head to slidably receive thread cutting dies, a cam rotatably mounted on said body and having an inwardly extending portion overlying the outer end of said body, said inwardly extending portion of the cam having circumferentially extending ribs projecting from its inner face into said sockets for engagement with said dies, said ribs being all inclined in the same direction with respect to their circumferential path of travel to simultaneously move said dies toward or away from the axis of said head, a handwheel rotatably mounted on said body inwardly of said head, a lost motion connection between said handwheel and cam including a link pivoted to said cam to swing radially and a cam carried by said handwheel for imparting angular movements to said link upon relative turning movements of said cam and handwheel, and a locking member operated by said link and movable from a position in which it holds the cam against turning movements with respect to said body to a position freeing the cam from said body.

6. A die head comprising a body portion having an inner end adapted for attachment to a driving spindle and an outer end formed to receive thread cutting dies, a die adjusting cam rotatably mounted on said body, a handwheel rotatably mounted on said body and having a cam slot that is inclined with respect to its circumferential path of travel, and a member pivoted intermediate its ends to said cam to swing transversely to the axis of the head, said member having a laterally projecting pin at one end extending into said slot to provide a lost motion connection between said handwheel and cam and a locking portion at its opposite end engageable with said body to hold said cam against turning movements with respect to said body, whereby said locking portion is moved to releasing position upon actuation of the handwheel during the turning movement of the handwheel with respect to said cam that is permitted by said slot.

7. A die head comprising a body portion having an inner end adapted for attachment to a driving spindle and an outer end formed to receive thread cutting dies, a die adjusting cam rotatably mounted on said body, a handwheel rotatably mounted on said body and having a cam slot that is inclined with respect to its circumferential path of travel, a ring rotatably mounted on said body between said handwheel and cam and provided with a recess, means for securing said ring to said body in various circumferential positions, a member pivoted intermediate its ends to said cam to swing radially, said member having a tooth at one end engageable in said recess and a pin at its opposite end extending into said cam slot, whereby said member is rocked about its pivot to release said tooth from said recess during the turning movement of the handwheel with respect to said cam permitted by said slot.

8. A die head comprising a body portion having an inner end adapted for attachment to a driving spindle and an outer end formed to receive thread cutting dies, a handwheel rotatably mounted on said body and having a cam slot that is inclined with respect to its circumferential path of travel, a retaining ring rotatably mounted on said body outwardly of said handwheel, said ring having an external recess and a projecting stop lug, a die adjusting cam rotatably mounted on said body outwardly of said ring, means for securing said ring to said body in various positions of circumferential adjustment, and a member positioned between said cam and handwheel and pivoted to said cam to swing toward and away from the axis of the head, said member having a tooth engageable in said recess, a pin projecting into said slot and a portion engageable with said stop lug to limit the turning movement of the cam with the handwheel.

9. A die head comprising a body portion having an inner end adapted for attachment to a driving spindle and an outer end formed to receive thread cutting dies, a handwheel rotatably mounted on said body and having a cam slot that is inclined with respect to its circumferential path of travel, a retaining ring rotatably mounted on said body outwardly of said handwheel, said ring having an external recess and a projecting stop lug, a die adjusting cam rotatably mounted on said body outwardly of said ring, means for securing said ring to said body in various positions of circumferential adjustment, a member positioned between said cam and handwheel and pivoted to said cam to swing toward and away from the axis of the head, said member having a tooth engageable in said recess, a pin projecting into said slot and a portion engageable with said stop lug to limit the turning movement of the cam with the handwheel, and a spring pressed member carried by said handwheel that slidably engages said member and exerts a radial pressure thereon to press said tooth inwardly toward its locking position.
